ABSTRACT: Fluid nozzle with an axial flow passage, an inlet of area less than that of the passage directly downstream thereof, and an even plurality of radial orifices into the passage arranged in coaxial pairs 180° apart.

PATENTED JUN 1 1971

3,581,992

FIG. 1

FIG. 2

FIG. 3

STREAMING

This invention relates to gas nozzles.

Objects of the invention are to enhance the directly useable (e.g., for liquid atomization) energy in gas streams, with small nozzles that can be simply and efficiently incorporated into a wide variety of physical processes.

The invention features a fluid nozzle with an axial flow passage, an inlet of area less than that of the passage directly downstream thereof, and an even plurality of radial orifices into the passage arranged in coaxial pairs 180° apart. In preferred embodiments the inlet is a circular hole in a thin plate; the passage is a counterbore to the inlet; circular holes into the passage surround the inlet, each being included in a pair of such holes spaced 180° apart at opposite sides of the inlet; four radial orifices spaced 90° apart are tangent to a countersink at the outlet end of the passage, the area of the inlet differing from the total area of the radial orifices by no more than half the area of any one of the radial orifices; and the nozzle has a flange at its outlet end adapting it for mounting in a tube to define an annular passage surrounding the tube and communicating with the radial orifices, the tube having an inlet opening of diameter approximately equal to that of the nozzle at its inlet end.

Other objects, features, and advantages of the invention will be apparent from the following description of a preferred embodiment thereof, taken together with the drawings thereof, in which:

FIGS. 1 and 2 are perspective views, from different vantage points; and

FIG. 3 is a vertical sectional view showing the nozzle of FIGS. 1 and 2 mounted, as preferred, in a cell.

Nozzle 10 has a cylindrical wall 12 (outside diameter 0.346 inch, inside diameter 0.260 inch) open at its outlet end across 45° countersink 14, which is surrounded by annular flange 16. Axial inlet 18 (diameter 0.177 inch) in end wall 19 is concentric with an imaginary circle (diameter 0.226 inch) containing the centers of eight equally spaced holes 20 (each of diameter 0.0315 inch). Four radial holes 22 (each of diameter 0.093 inch) in wall 12 have coplanar axes spaced 90° .

The nozzle is mounted in cell 30 (largest inside diameter 0.431 inch) with flange 16 tightly secured in counterbore 32 against flange 34 (inside diameter 0.398 inch). Cell 30 has an inlet hole 36 (diameter 0.345 inch) in end wall 38.

Additional dimensions of the assembly are:

	Inch
Length of tube 30 between downstream face of wall 38 and upstream face of counterbore 32.	0.267
Length of nozzle 10 between wall 19 and countersink 14	0.221
Depth of countersink 14	0.029

In operation, air at greater than atmospheric pressure (e.g., at between $\frac{1}{4}$ and 20 p.s.i.g.) is supplied to inlet 36 and flows through nozzle inlet 18, and holes 20 and 22, and out of the nozzle across countersink 14.

Liquid can very effectively be atomized by, e.g., introducing the liquid with the air at inlet 36 or through holes 22, or by causing the stream leaving the nozzle to impinge upon the liquid, even at a distance of several inches or more.

Other embodiments will occur to those skilled in the art and are within the following claims.

What I claim is:

1. A fluid nozzle, comprising a body defining an axial flow passage having inlet and outlet ends,

a portion at said inlet end defining an axial inlet to said passage, the area of said inlet being less than the area of said passage directly downstream thereof, openings into said passage being provided in said portion radially outwardly of said axial inlet, and

an even plurality of radial orifices in said body between said ends, said orifices communicating with said passage and being arranged in coaxial pairs 180° apart.

2. The nozzle of claim 1 wherein said passage has a cylindrical wall and said inlet is of circular cross section.

3. The nozzle of claim 2 wherein said passage is a counterbore to said inlet.

4. The nozzle of claim 1 wherein said body has a countersink at said outlet end.

5. The nozzle of claim 1 wherein said portion is a thin wall.

6. The nozzle of claim 1 wherein said openings are holes of circular cross section, each being included in a pair of said holes spaced 180° apart at opposite sides of said axial inlet.

7. The nozzle of claim 2 wherein said radial orifices are directly adjacent the outlet end of said cylindrical wall.

8. The nozzle of claim 7 wherein said body has a countersink at said outlet end of said passage, directly downstream of said cylindrical wall and tangent to said radial orifices.

9. The nozzle of claim 1 wherein there are four of said radial orifices spaced 90° apart.

10. The nozzle of claim 1 wherein said area of said inlet differs from the total area of said radial orifices by no more than half the area of any one of said radial orifices.

11. A fluid nozzle, comprising a body defining an axial flow passage having inlet and outlet ends,

a portion at said inlet end defining an axial inlet to said passage, the area of said inlet being less than the area of said passage directly downstream thereof, and

an even plurality of radial orifices in said body between said ends, said orifices communicating with said passage and being arranged in coaxial pairs 180° apart,

said body having at said outlet end a flange extending radially outwardly of said orifices, whereby said nozzle is adapted to be mounted in a tube with said flange in contact with the inner wall of said tube, so that said tube and said body define upstream of said flange an annular passage surrounding said nozzle and communicating with said orifices, said tube being larger than said body and having an inlet opening of a diameter approximately equal to that of said body at said inlet end.
